UNITED STATES PATENT OFFICE.

THOMAS JAMES, OF MORRISTON, ENGLAND, ASSIGNOR TO GRIFFITH THOMAS, OF COURT HERBERT, ENGLAND, AND DAVID MATTHEWS, OF MORRISTON, ENGLAND.

AUTOMATIC PLATE-CARRIER FOR USE IN THE MANUFACTURE OF TIN AND TERNE PLATES.

No. 895,024.

Specification of Letters Patent.

Patented Aug. 4, 1908.

Application filed October 17, 1907. Serial No. 397,827.

To all whom it may concern:

Be it known that I, THOMAS JAMES, a subject of the King of Great Britain and Ireland, and resident of Vine House, Crown street, Morriston, county of Glamorgan, Wales, England, have invented certain new and useful Improvements in Automatic Plate-Carriers for Use in the Manufacture of Tin and Terne Plates, (for which I have obtained a patent 10 in Great Britain, No. 23,899, bearing date October 26, 1906,) of which the following is a specification.

My invention relates to that part of the process of tin and terne plating in which the 15 plates have to be removed from the "grease pot" and transferred to the "branning machine".

The object of the invention is in the main to avoid the forming of a "list" or extra 20 thickness of tin or alloy near that edge of the plate which last leaves the tinning rolls, and further to obviate the necessity for lifting the plates from the last rolls in the tinning bath with the aid of tongs.

25 The invention consists in causing the edge of the plate to leave the tinning roll in a plane which is not tangential to the roll but which would cut the roll if it were produced backwards; by this means the edge of 30 the plate is "wiped" by the roll and the superfluous tin removed, and this result is attained by means of a series of guide bars and 35 guide rollers mounted in a frame hinged to the top of the tinning trough, which bars and rollers receive the plates from the tinning rolls and serve subsequently to guide them to any well known apparatus for transferring them to the branning machine.

The accompanying drawings illustrate the 40 way in which the invention is carried into effect.

Figure 1 is a side elevation of the apparatus. Fig. 2 is a part plan view with the cover and wiping brushes removed. Fig. 3 45 is a side elevation showing the apparatus hinged up so that the parts may be cleaned or repaired. Figs. 4 and 5 are diagrams to illustrate the manner in which the plate should leave the tinning rolls.

50 In these views a represents the grease trough, and a' , a'' the last pair of tinning rolls. These rolls are driven together by means of gear wheels b' , b'' . Hinged to each end of the

top of the trough is a plate c and these plates together with the cross bars form a frame on 55 which are mounted the guide rollers and guide bars now to be mentioned.

When the tin plate (represented by the dotted line x Fig. 1) rises from the last pair of rolls it meets with an upper series of guide 60 bars d mounted on a cross bar e fastened between the plates c . These guide bars have a slot and bolt arrangement intermediate of their length as shown for the purpose of adjustment. I find it advantageous though 65 not absolutely necessary to employ a horizontal bar d' bolted to the lower ends of the bars d to exercise a wiping action on the outer surface of the tin-plate near its edge when it has completely issued from the rolls, 70 as hereinafter described.

A lower set of guide bars f co-operates with the upper set d , and have a similar arrangement for adjustment. They are bolted to the cross bar g . These bars f are adjusted so 75 as to cause that portion of the traveling plate which has passed through the rolls to keep an upright position, but as the edge leaves the rolls the upright position is lost. If the plate were to leave the rolls vertically 80 as shown diagrammatically in Fig. 4 it would take up an extra quantity of tin (called the "list") near its lower edge and it is an object of my invention to avoid this. Fig. 5 shows 85 the manner in which the guide rods d , f co-operating with the elasticity of the tin-plate cause it to leave the rolls, not tangentially, but in a path which cuts the circle of the roll a' . The tin-plate next comes into contact with a series of guide rolls h mounted on a 90 spindle which runs freely in bearings in the side plates c , and next with a series of guide rolls k . These rolls k are mounted on a spindle fitted with a chain wheel l which is driven from a chain wheel m , mounted freely 95 on a spindle n and fast with a gear wheel o which, when the frame is down in the driving position in Figs. 1 and 2, gears with the gear wheel b' of the roll a' . The spindle n is mounted in a plate q which is adjustable on 100 the frame plate c . A series of guide bars r serve to conduct the plates to the branning machine or to some intermediate device.

s , s' are wiping brushes which may be allowed to impinge on the guide rolls to remove any excess of grease. 105

Having now described my invention what I claim as new and desire to secure by Letters Patent of the United States is:—

1. In a tin and terne plate carrying mechanism, a frame, curved guides on the frame, rolls for drawing plate from a bath, a bar connecting the ends of the guides acting to wipe the plate passing from the rolls to the guides.
- 10 2. In a tin and terne plate carrying mechanism, curved guides arranged in pairs, rolls for drawing plate from a bath, means for suspending the ends of the guide above the rolls whereby the plates from the rolls are directed to the guides and means on the lower ends of the guides for wiping the plates.
- 20 3. In a tin and terne plate carrying mechanism, rolls for drawing plates from a bath, curved guides arranged one above the other having their ends suspended above the rolls and a device secured to one of a pair of guides for wiping the plate passing between the guides.
- 25 4. In a tin and terne plate carrying mechanism, a frame, jointed guiding members car-

ried thereon, means for adjusting the relation of the guiding members to each other, means for delivering plates to the guiding members and means on the ends of the guiding members for wiping the plates.

5. In a tin and terne plate carrying mechanism, a frame, means for supporting the frame and permitting it to swing on its pivots, jointed guiding members carried on the frame, means for adjusting the relation of the guiding members to each other and means for delivering plates to the guiding members.

6. In a tin and terne plate carrying mechanism, a frame, jointed guiding members carried thereon, means for adjusting the relation of the guiding members to each other, means for delivering plates to the guiding members and means for feeding the plates longitudinally of the said members.

In testimony whereof I have affixed my signature in presence of two witnesses.

THOMAS JAMES.
